SINGLE GUTTER BARN CLEANER

Nat Cordis, Silver Lake, Wis.

Application March 13, 1950, Serial No. 149,320

8 Claims. (Cl. 198—170)

1

This invention relates to improvements in mechanical barn cleaners and more particularly to a barn cleaner of the type employing a conveyor chain and paddles or scrapers attached to the chain which travel within a gutter to a point of discharge.

Many types of barn cleaners have been proposed heretofore but none is adapted to rapidly and thoroughly clean a single gutter arranged behind a row of stalls. It is, therefore, a principal object of my invention to provide an improved barn cleaner and conveyor which is particularly adapted for operation in a single gutter in a barn floor. Another object of this invention is to provide a combination barn cleaner and conveyor which provides a compact assembly for discharge of refuse at one end of a single gutter and a turn-around at the other end with minimum of space requirements and a minimum alteration of already existing barn floors and gutters. Further objects and advantages of my invention will become apparent as the description thereof proceeds.

Briefly my invention comprises an endless chain conveyor arranged to travel in a gutter and over an aligned chute. Paddles or scrapers are adapted to project laterally from a single strand of the conveyor chain but are hinged to spaced links so that they may be swung 180 degrees in planes extending transversely of the chain. The chain runs on only one side of the trough assembly over idler and drive sprockets which are adjustably mounted for rotation in a plane substantially parallel to the wall of the gutter. In one direction the conveyor and paddles move along the bed of the gutter and in the reverse direction the chain is substantially flush with the barn floor at the edge of the gutter and the paddles or scrapers travel over the floor, a position which is attained by pivoting the paddles 180 degrees about the chain link from the normal cleaning position on the bed of the gutter. At the dead or closed end of the gutter and at the discharge end of the chute, novel turn-around assemblies are provided for shifting the relative position of the paddles.

A limited number of paddles are fixed to only that portion of the total length of the conveyor chain which can be accommodated within the gutter and chute when the cleaner is not in motion. By this means, when the apparatus is in an inactive position, all of the paddles can be arranged within the gutter and chute and none of the paddles obstructs the floor area adjacent the gutter.

2

My invention will be better understood by reference to the following detailed description of a preferred embodiment and to the attached drawings forming part thereof. Like reference characters indicate corresponding parts in the various figures wherein:

Figure 1 is an elevation of my device arranged within a barn floor gutter;

Figure 2 is a top plan view of the embodiment illustrated in Figure 1;

Figure 3 is a cross-section along the line 3—3 in Figure 1 showing the turn-around mechanism at the closed end of the gutter;

Figures 4 and 5 are top and side views, respectively, of the mechanism for adjustably supporting the idler sprocket at the dead end of the gutter as shown in Figures 1 and 2; and

Figures 6 and 7 are side and top views, respectively, of a chain structure and paddle mount 20 which may be used in my invention.

Referring to the drawing, the channel or gutter 10 is arranged behind cattle stalls and is provided at one end with an outlet conveyor trough 11 which discharges at a point elevated 25 from the main channel 10. An endless conveyor 12 passes along the bottom of the channel 10 and is caused to travel in this position by means of sprockets 13 and 14 arranged at each end of the assembly. When the conveyor chain 12 reaches the lower end of the discharge conveyor 30 chute 11 it passes upwardly over the floor of the conveyor trough and is guided by the pulleys 15.

The conveyor chain 12 runs on only one side 35 of the trough 10 and is provided with only a limited number of paddles 16 which are pivoted to it and extend outwardly across the channel or gutter 10 in a rigid array. The length of the endless chain or conveyor 12 which is 40 equipped with paddles is approximately $\frac{1}{2}$ the total length of the conveyor chain. Thus, when the apparatus has been used to clean the trough 10, only that portion of the chain having paddles is retained within the trough assembly whereas 45 that portion of the chain which is stored at the upper edge of the gutter wall is free of any paddles. By this arrangement the paddles 16 do not interfere with the cattle and yet an optimum number of scraping elements is provided for the cleaning operation. It will be 50 recognized, however, that in some instances it may be desirable to employ a greater number of paddles than that which can be accommodated within the trough assembly.

55 Reverting to the direction of the travel of the

conveyor chain 12, after passing under the pulleys 15 it is driven upwardly over the discharge chute 11 to the point of discharge 17 above the hopper 18. There the paddle 16 swings downwardly and is guided by disc 19 in a substantially radial direction about the drive sprocket 14. After the paddle 16 has traveled upwardly about the sprocket 14, it is deflected by fender 20 so that the paddle is pivoted laterally about 180 degrees from its former position in traveling through the gutter 10. The fender 20 is fixed to the frame 21 and extends along the face of guide disc 19 to positively shift the paddles 16 about the conveyor chain 12.

The paddles 16 then travel along the guide strip 23 until it reaches the barn floor. A channel bar 24 guides the chain downwardly and feeds the conveyor chain 12 into a slotted channel guide means 25. The conveyor chain 12 and scraper paddle 16 then travel along the upper edge of the gutter wall 10a, the chain being supported, if desired, by chain support 26. As the chain and scraper near the dead end turn-around assembly comprising the chain guide, paddle deflector, idler sprocket and paddle disc guide, the chain enters a second slotted channel guide means 27 as shown in Figures 2 and 3. The paddle 16 travels up the deflector rod 28 until it is pivoted about the chain 12 onto the guide rod 29. The paddle 16 then continues over the guide disc 30 and the chain 12 passes over the idler sprocket 13 until the circuit has been completed and the scraper 16 is once more traveling along the bottom of the trough 10.

A suitable drive mechanism for the conveyor chain and paddles is shown in Figures 1 and 2. A motor 33 drives a gear 34 and chain 35 which in turn drives sprocket 14 through gear 36 and shaft 37. It should be understood that other means for driving the chain may be used but since this is not a primary aspect of the invention, the drive mechanism need not be described in greater detail. Many such mechanisms, however, are available to the men skilled in the art.

Although I have illustrated the discharge end 11 of the trough 11 as being elevated and as being supported by a framework 21 it should be understood that the hopper 18 may be recessed below the level of the gutter 10 and, in that event, it will not be necessary to elevate the discharge end of the assembly. If it is not elevated, then the guide pulleys 15 are not essential and, if desired, the drive mechanism 33-34-35 can be mounted above the trough instead of below the trough as illustrated in Figure 1.

Referring to the idler or turn-around assembly, Figures 4 and 5 illustrate a means for adjusting the tension of the conveyor chain 12 during use. The housing 40 of the turn-around assembly is provided with a slot 41 accommodating the shaft 42 on which is mounted the sprocket 13 and the guide disc 30. The shaft 42 is in turn fixed within the adjustable shaft terminal 43 slidably held at an angle on the housing 40 corresponding to the pitch of the slot 41. The take-up bolt 44 and nuts 45-46 can then be adjusted to move the idler sprocket shaft 42 outwardly or permit it to move inwardly so as to maintain the desired tension on the chain assembly. The take-up bolt 44 is placed in compression between thrust plate 47 and anchor plate 48, the latter being fixed as by bolting or by welding to the housing 40.

A number of different types of chain may be used and I have illustrated in Figures 6 and 7 one form of chain which is described and claimed

in my co-pending application, Serial No. 92,553, filed May 11, 1949 and entitled De-Mountable Chain for Barn Cleaner. In this chain structure I employ an apertured central link 50, parallel side bars 51, and pintles 52 connecting said central link 50 and alternate pairs of parallel side bars 51. The side bars 51 have apertured slots through which the pintles 52 extend. A clip 54 for retaining the removable side bars 51 of the chain comprises a resilient sheet substantially co-extensive with the side bar and is provided with open pintle engaging slots at each end of the sheet. This clip maintains the pintles 52 in spread position and in bearing contact with side bars 51 at the ends of the slots 53 therein.

One means of mounting the scraper paddle 16 is illustrated in Figures 6 and 7 wherein a pair of trunnions 55 are welded to the edge of the central link 50. The paddle 16 is pivotally fixed between the trunnions on the bolt or pin 56. A block 57 is welded to the angle iron scraper element 16 to provide a suitable bore for the pin 56. It is contemplated, however, that one edge of the angle iron 16 can be bent upon itself parallel to the other side of the angle iron to provide two aligned holes through which the pin 56 can be supported. Obviously, the elements should be arranged in such a manner that the chain bar 50 does not interfere with the rotation of the scraper about 180 degrees around the pin 56.

Although I have illustrated and described a preferred embodiment of the invention, it should be understood that variations and modifications may be made therein without departing from the spirit of the invention. As pointed out, other types of chain constructions are contemplated and other means provided for pivotally mounting the scrapers about the chain. Likewise, wooden scrapers can be substituted for the angle iron paddles illustrated in the drawings. Accordingly, I do not wish to be limited to the precise details disclosed but intend to include such modifications and embodiments which will be apparent to those skilled in the art from the above description of my invention.

What I claim is:

1. In a barn cleaner for a gutter in a barn floor adjacent cattle stalls, an endless conveyor means including a sprocket chain mounted to travel along one wall through said gutter, the cleaning run of said conveyor means travelling over the bed of said gutter and the return run of the conveyor means travelling at the upper edge of the gutter, conveyor flights pivotally mounted on said sprocket chain, means at one end of said gutter for deflecting said flights 180 degrees about said chain from their normal position of travel over the bed of said gutter, whereby the flights travel over the floor of the barn adjacent the edge of the gutter on the return run, and a fender means at the other end of said gutter adapted to deflect said flights 180 degrees from the floor level, thereby restoring the flights to an operative position in the bed of said gutter.
2. In a barn cleaner for a gutter in a barn floor adjacent cattle stalls, a single endless conveyor means including a sprocket chain mounted to travel along one wall through said gutter, a drive sprocket and an idler sprocket mounted to rotate in a plane parallel to the wall of said gutter whereby the said conveyor means travels over the bed of said gutter in one direction and at the upper edge of the gutter in the reverse direction, conveyor flights pivotally mounted on said sprocket chain, means at one end of said gutter

for deflecting said flights 180 degrees about said chain from their normal position of travel over the bed of said gutter, whereby the flights travel over the floor of the barn adjacent the edge of the gutter, and a fender means at the other end of said gutter adapted to deflect said flights 180 degrees from the floor level before travel about the idler sprocket, thereby restoring the flights to an operative position in the bed of said gutter.

3. In a cleaner for a gutter in a barn floor adjacent cattle stalls, a discharge section comprising an inclined chute aligned with one end of said gutter, a single endless conveyor chain mounted to travel through said gutter and over said chute, the return run of the conveyor chain travelling at the upper edge of the gutter, conveyor flights pivotally mounted on said endless conveyor chain, means adjacent said discharge chute for deflecting said flights 180 degrees from their normal position of travel through said chute, whereby the flights extend laterally of the gutter and travel over the floor of the barn adjacent the edge of the gutter, and a fender means at the other end of said gutter adapted to deflect said flights 180 degrees from the floor surface thereby returning the flights to an operative position in said gutter.

4. An endless conveyor means including a gutter open at one end and closed at the other end, a sprocket chain mounted to travel through said gutter along the wall thereof, the cleaning run of said chain travelling over the bed of said gutter and the return run of the conveyor means travelling at the upper edge of the gutter, conveyor flights pivotally mounted on said sprocket chain, means at the open end of said gutter for deflecting said flights 180 degrees about said chain from their normal position of travel over the bed of said gutter, whereby the flights travel over the floor of the barn adjacent the edge of the gutter on the return run, and a fender means at the closed end of said gutter adapted to deflect said flights 180 degrees from the floor level, thereby restoring the flights to an operative position in the bed of said gutter.

5. In a barn cleaner for a gutter in a barn floor adjacent cattle stalls, an endless conveyor means including a sprocket chain mounted to travel through said gutter along one wall thereof, said conveyor means travelling over the bed of said gutter and along the upper edge of the wall of the gutter, conveyor flights pivotally mounted on said sprocket chain, means adjacent said point of discharge for deflecting said flights about said chain from their normal position of travel through said gutter to a position parallel to the barn floor, whereby the flights travel over the floor of the barn adjacent the edge of the wall of the gutter on the return run, and a fender means at the other end of said gutter adapted to deflect said flights from the floor level to a position parallel to the bed of the gutter, thereby restoring the flights to an operative position in the bed of said gutter.

6. A barn cleaner adapted to be installed in a barn floor gutter comprising an inclined discharge chute aligned with one end of said gutter, an idler turn-around assembly within the other end of the gutter, an endless conveyor chain mounted for travel over sprockets fixed to rotate in a plane parallel to one wall of said gutter, the return run of said chain travelling near the upper edge of said gutter wall above the cleaning run of chain, a plurality of spaced conveyor flights mounted on a portion of said endless conveyor chain and adapted to pivot 180 degrees

about said chain, means adjacent said chute for deflecting said flights 180 degrees from their normal operative position of travel over the bed of said gutter and over said chute whereby the flights travel over the floor of the barn at the edge of the gutter, and a fender means in said turn-around assembly adapted to lift said flights and deflect them 180 degrees onto a rotatable guide disc, thereby returning the flights to the initial operative position in said gutter.

7. A barn cleaner adapted to operate in a refuse gutter associated with a line of cattle stalls, the apparatus which comprises an inclined discharge chute aligned with the first end of said gutter, a turn-around assembly adjacent the second end of said gutter, an idler sprocket within said turn-around assembly, a drive sprocket adjacent the discharge end of said chute, an endless conveyor chain mounted for travel along one wall of said gutter and of said chute, a slotted channel means for guiding the return run of chain at the junction of the lower end of said chute with said gutter, a plurality of spaced scraper flights mounted on said endless conveyor chain and adapted to pivot about said chain 180 degrees, deflecting means mounted beyond the end of said chute for shifting said flights to a position which is 180 degrees from their normal operative position of travel over the bed of said gutter and said chute whereby the flights are caused to travel over the floor of the barn at the edge of the gutter, a second channel means for guiding the upper run of the chain upwardly over the idler sprocket, and a fender means in said turn-around assembly adapted to lift said flights and deflect them 180 degrees from the floor of the barn whereby the flights are returned to their operative position for passage over the bed of said gutter.

8. In a straight-line barn cleaner for a gutter in a barn floor adjacent cattle stalls, an endless conveyor means including a sprocket chain mounted to travel through said gutter along one wall thereof, the cleaning run of said chain travelling adjacent the bed of said gutter and the return run of the chain travelling near the upper edge of the gutter, a plurality of scraper flights extending laterally from said chain across said gutter, said flights being pivotally mounted on said chain, means at one end of said gutter for deflecting said flights upwardly about said chain from their normal position of travel over the bed of the gutter to a position wholly outside the gutter, whereby the flights travel outside the gutter above the floor level on the return run, and a fender means at the other end of said gutter adapted to deflect said flights across the gutter, thereby restoring the flights to an operative cleaning position in the bed of said gutter.
